AUTOMATIC FLAP CONTROL FOR
AIRPLANESErich Gast, Dessau, Germany; vested in the Alien
Property CustodianApplication October 23, 1940, Serial No. 362,425
In Germany July 10, 1939

11 Claims. (Cl. 244—78)

This invention relates to automatic flap controls for airplanes. The use of flaps and the like for increasing the lifting power of airplanes is constantly increasing, and experience has shown the need of means for automatically returning these flaps to or towards their inoperative positions when the air pressure exerted against them exceeds a predetermined maximum and threatens to become dangerous.

To this end arrangements have been devised which have not proved entirely satisfactory. For instance hydraulic means have been employed having relief valves set to open at certain pressures and thereby permit the return of the flaps to their inoperative positions when the air pressure acting against them becomes excessive. Due, however, both to the friction to be overcome in the mechanism itself and the wind resistance against which the flaps have to be moved to their operative positions it is often found impossible to use such an arrangement because the pressure required to overcome both the friction and the air resistance to move the flaps outwardly is greater than that required merely to retain the flaps in operative position even when they are subjected to such excessive air pressure as to threaten their destruction. The next step then was to provide a form of relief valve including means for rendering it inoperative during the outward movement of the flap, but then if the flap during its outward movement were subjected to excessive air pressure the relief valve would remain inoperative and destruction of the flap might result. A further difficulty in such an arrangement lay in the fact that the friction in each installation varied to such an extent that the valve setting was a tedious job involving a number of test flights, and often then only resulted in a more or less approximately correct setting.

It is an object of this invention to provide an automatic flap control by which the above named drawbacks are overcome, and wherein more sensitive means are provided for moving the flap to its operative position and retaining it in that position unless and until the air pressure acting against it exceeds a predetermined limit, and when that limit is exceeded moving the flap to or towards its inoperative position until the air load acting against it drops below the aforesaid limit, whereupon the flap is again moved to its operative position.

Another object of the invention is to provide an automatic flap control including a hydraulic cylinder having a piston therein adapted to move

the flap, and to mount the cylinder for movement so that through this movement the flap inclination may be varied.

5 A further object of the invention is to provide such an automatic flap control wherein the cylinder is supported by a lever one extremity of which moves between stops against one of which the lever is normally held; and wherein a mechanism operated by movement of the lever releases the pressure in the hydraulic feed line to the cylinder.

10 Yet another object of the invention is to provide such an automatic flap control wherein means are provided for preventing fluttering of the flap during movement of the lever and cylinder.

15 Another object of the invention is to provide such an automatic flap control wherein the hydraulic circuit may be either mechanically or electrically controlled.

20 Still another object of the invention is to provide an automatic flap control in one embodiment of which movement of the lever from its normal position breaks an electric circuit and 25 cuts off the hydraulic flow to the cylinder whereby the flap is moved to and retained in its operative position, and wherein upon completion of the pivotal movement of the lever a second electric circuit is closed whereby the hydraulic system 30 is set to permit movement of the piston in the cylinder by which the flap is returned to its inoperative position.

Having thus briefly and broadly stated some 35 of the objects and advantages of the invention I will now describe two preferred embodiments thereof with the aid of the accompanying drawing, in which:

Figure 1 illustrates a diagrammatic view of the 40 invention wherein the hydraulic flow is mechanically controlled, and

Figure 2 shows a modification thereof wherein the hydraulic mechanism is electrically controlled.

45 Referring to Figure 1, 1 denotes a tank connected by a suction pipe 2 to a pump 3 from which liquid under pressure is delivered to a rotary valve 5 through a discharge pipe 4 from which a return line 10, having a relief valve 9 therein, extends back to the tank 1 to limit the 50 pressure of the liquid discharged by the pump.

The rotary valve 5 has four connections; one connected to the discharge pipe 4, one to a return connection 11 extending back to the tank 1, one to a flap operating line 12, and one to a flap 55 return line 16; provided in this valve is a rotary

plug 5a having three separate passages 6, 7 and 8 formed therethrough. By the passage 6 the discharge pipe 4 is shown connected to the return connection 11, and the passages 7 and 8 are then inoperative. However by turning the plug 5a, the discharge pipe 4 may be connected through the passage 8 to the flap operating line 12 at which time the flap return line 16 is connected by the passage 7 to the return connection 11, or the discharge pipe 4 may be connected to the flap return line 16 through the passage 7 at which time the flap operating line 12 is connected through the passage 8 with the return connection 11. When the rotary plug 5a is in either of these latter positions the passage 6 is inoperative.

Pivoted on a pin 21, supported from a fixed portion of an airplane, is a lever 22 mounted for movement on one extremity of which is a cylinder 14 having a piston 17 therein from which a rod 18 extends. Pivoted on a pin 19 supported by another fixed portion of the airplane is a flap 20 to which the outer extremity of the rod 18 is so connected that movement of the piston 17, or of the cylinder 14 when the piston remains stationary therein, causes movement of the flap 20 about the pin 19. The flap operating line 12 and the flap return line 16 are connected to opposite ends 13 and 15 of the said cylinder respectively, and, since the cylinder is intended to move somewhat when the lever 22 swings about its axis, the lines 12 and 16 are made sufficiently flexible to permit such movement.

The extremity of the lever 22 remote from the cylinder 14 extends between two stops 24 and 25 mounted on fixed portions of the airplane, and which limit the swinging of the lever 22 in both directions. Mounted also on a fixed portion of the plane and in threaded engagement therewith is an adjusting screw 23' having one extremity of a coil spring 23 secured thereto and its opposite extremity secured to the free end of the lever 22. This spring tends to retain the lever 22 against the stop 24 and the cylinder 14 in its position shown; by adjusting the screw 23' the tension of the spring may be varied. Thus maximum air pressure to be withstood by the flap 20 when turned to its operative position, before movement of the lever 22 about the pivot pin 21 and therefore movement of the cylinder 14 occurs, may be varied.

Extending from the flap operating line 12 is a branch 12a terminating in a valve chamber 28 having a piston valve 27 therein. A rod 26 extends between and is connected at opposite extremities to the lever 22 and to the valve 27. Extending also from the valve chamber 28 is a relief line 11a from which a circulating pipe 33 extends having a relief valve 32 therein and connected at its opposite extremity to the flap return line 16; the relief line 11a is also preferably connected to the return connection 11 through a pressure retaining valve 31 set to open at a higher pressure than the valve 32. The opposite ends of the valve chamber 28 are connected by a by-pass pipe 29 having a suitable valve 30 therein to retard the flow of liquid in either direction through the said pipe and prevent rapid reciprocation of the piston valve 27 and consequent fluttering of the flap 20 about the pin 19.

To move the flap 20 to its operative position the rotary valve 5 is so turned that the discharge pipe 4 is connected to the flap operating line 12 and the return connection 11 to the flap return line 16. Then hydraulic pressure is exerted in the

end 13 of the cylinder 14 and the flap 20 is turned about its axis by outward movement of the rod 18. When the air pressure exerted against the flap, then in inclined position, exceeds a predetermined limit, set by the tension of the spring 23, the cylinder is moved substantially axially as the lever 22 swings about its pin 21 away from the stop 24, and if during this movement excessive air pressure continues to be exerted against the flap the lever continues to swing until it strikes the stop 25. During the first part of the swinging movement of the lever 22 towards the stop 25 the piston 17 is held stationary in the cylinder 14 by hydraulic pressure from the flap operating line 12, but when the lever has moved sufficiently to cause such movement of the piston valve 27 that the branch 12a is connected with the relief line 11a through the valve chamber 28 then liquid under pressure flows from the flap operating line 12 through the circulating pipe 33 and the relief valve 32 to the flap return line 16 and thus to the cylinder end 15. Then the flap 20 is swung back towards its inoperative position by movement of the piston 17 pushed inward by air pressure exerted against the flap 20. However as soon as the air pressure acting against the flap drops below that for which the spring 23 is set, that spring moves the lever 22 back towards the stop 24 thereby moving the piston valve 27 to sever the connection between the branch 12a and the relief line 11a, whereupon pressure is again built up in the cylinder end 13 and at the same time the cylinder 14 is moved forward towards its normal position.

If it is desired to render the flap 20 inoperative for normal flight the valve 5 is so set that the discharge pipe 4 is connected to the flap return line 16, and the flap operating line 12 to the return connection 11. The pressure is exerted in the cylinder end 15 which retains the piston 17 at its rear position in the cylinder 14.

In the modification shown in Figure 2 the same mechanism is electrically instead of mechanically operated. The tank 1, suction pipe 2, pump 3, discharge pipe 4, and return line 10 with its relief valve 9 are again employed. The discharge pipe 4 is connected to a valve 34 to which a return connection 11 and an actuating pipe 46 are also connected. In the valve 34 is a plunger 37 which is normally retained in its position shown by a spring 40 so that the discharge pipe 4 is connected to the return connection 11. However by energizing the solenoid 43 through an electric circuit hereinafter described the plunger 37 is moved to close the return connection 11 and afford communication between the discharge pipe 4 and the actuating pipe 46. The latter terminates in a valve 35 having a plunger 38 therein normally retained in its position shown by a spring 41 so that the actuating pipe 46 is normally connected to a flap operating line 12b which terminates in the end 13 of the cylinder 14. Extending from the valve 35 is also a flap return line 16b which terminates in the end 15 of the said cylinder and which is connected to the actuating line 46 upon movement of the plunger 38 by the solenoid 44, whereupon connection between the actuating pipe 46 and the flap operating line 12b is interrupted.

Extending from the return connection 11 is a relief line 11b having a pressure retaining valve 31a therein and terminating at its opposite extremity in a valve 36, between which and the said valve 31a a circulating pipe 33a is provided which connects the relief line 11b with the actuating

pipe 46 and has a relief valve 32a therein. A plunger 39 in the valve 36 is normally so held by a spring 42 that the relief line 11b is connected to a branch 16' of the flap return line 16b, but when the plunger 39 is moved by a solenoid 45 it connects the relief line 11b with a branch 12' of the flap operating line 12b.

The arrangement of the cylinder 14 with its piston 17 and rod 18 connected to the flap 20 pivoted on a pin 19 is the same as before, and the cylinder is again secured to the pivoted lever 22 the free extremity of which swings between the two stops 24 and 25 and is normally retained against the stop 24 by a spring 23 the tension of which is adjustable through the adjusting screw 23'. Spring contacts 47 and 48 remain at all positions of the lever 22 in contact with the latter adjacent its free extremity, and the lever is so constructed as to constitute insulation between the contacts 47 and 48. When the lever is in the position shown the contact 47 is in electrical engagement with the stop 24 which also functions as an electrical terminal, and then the contact 48 is disengaged from the stop 25 which functions also as a terminal.

From a source of power 60 a lead 61 extends to the solenoid 43, and from the latter another wire 62 runs which is connected to the spring contact 47. When the lever 22 is in the position shown this contact 47 is in electrical engagement with the stop 24 from which a wire 63 extends to one side of a switch 49, the opposite side of which is connected through a lead 64 to the source of power 60. Thus when the switch 49 is closed the solenoid 43 is operative whenever the lever 22 is in its position shown. At that time a hydraulic flow occurs from the discharge pipe 4 through the actuating pipe 46, valve 35 and flap operating line 12b to the cylinder end 13, thereby moving the piston 17 and rod 18 forward and turning the flap 20 to its operative position. Then liquid displaced from the cylinder end 15 flows through the flap return line 16b and branch 16' through the valve 36, the relief line 11b, valve 31a and return line 11 back to the tank 1.

When the lever 22 swings away from the stop 24 the circuit through the spring contact 47 and solenoid 43 is broken, and the spring 40 returns the plunger 37 in the valve 34 to its position shown and closes the connection between the discharge pipe 4 and the actuating pipe 46, and opens the former to the return connection 11. Due to the provision of the relief valve 31a in the relief line 11b all the liquid then flows back to the tank 1. When the lever 22 moves the spring contact 48 into electrical engagement with the stop 25 a circuit is closed through a wire 61' extending from the lead 61 to the solenoids 44 and 45, from the latter through a wire 65 connected to the stop 25 and from the contact 48 through a wire 64' connected to the wire 64. Then the plungers 38 and 39 are so moved that the following flow results as the piston 17 is moved to the left (Figure 2) by air pressure acting against the flap 20: From the cylinder end 13 to the end 15 through the flap operating line 12b and branch 12', valve 36, relief line 11b, circulating pipe 33a and valve 32a, actuating line 46, valve 35 and flap return line 16b.

A third electric circuit is provided for directing the hydraulic flow so that the flap 20 is positively maintained in its inoperative position shown. This consists of a double switch 60 having connections 65' and 62' connected to the wires 65 and 62 respectively, both of which, when the

switch is closed, are connected to a lead 64. Obviously when the switch 60 is closed all three solenoids are energized. Then a hydraulic flow occurs from the discharge pipe 4, through the valve 34, actuating pipe 46, valve 35 and flap return line 16b, at which time the flap operating line 12b is connected through its branch 12', and valve 36 to the relief line 11b and through the valve 31a to the tank 1.

While in the foregoing the preferred embodiments of the invention have been described and shown it is understood that further alterations and modifications may be made thereto provided the said alterations and modifications fall within the scope of the appended claims.

What I claim is:

1. An arrangement of the character described comprising a pivoted lever, a cylinder mounted for substantially axial movement on one extremity of the lever, means tending to retain the lever at one end of its travel and the cylinder in its normal position, a piston in the cylinder, means for introducing a pressure medium into the cylinder for moving the piston, a movable flap adapted to be moved from an inoperative to an operative position to afford resistance to an air stream, a rod connected to the piston and to the flap for moving the latter, and said flap being adapted to be moved from its operative towards its inoperative position by excessive air pressure thereby moving the cylinder and lever while the piston is held stationary in the cylinder by the pressure medium.

2. An arrangement comprising the combination set forth in claim 1, wherein the means tending to hold the cylinder at one limit of its travel consists of a spring which returns the cylinder to its normal position and thereby returns the flap to its operative position when the air pressure acting against the latter drops below a predetermined amount.

3. An arrangement comprising the combination set forth in claim 1, wherein the means tending to hold the cylinder at one limit of its travel consists of a spring, and means for adjusting the tension of the latter whereby the air pressure required to move the flap towards its inoperative position and the cylinder substantially axially may be varied.

4. An arrangement of the character described comprising a pivoted flap adapted to be moved from an inoperative to an operative position to offer resistance to an air stream, a cylinder mounted for limited movement substantially in alignment with its axis, a spring normally retaining the cylinder at one end of its travel, a piston in the cylinder, a rod extending from the piston and connected to the flap to impart pivotal movement thereto, and hydraulic means for moving the piston in the cylinder, said flap when in operative position being adapted to be turned towards its inoperative position by excessive air pressure exerted against it thereby moving the cylinder against the tension of the spring while the piston remains stationary in the cylinder.

5. An arrangement of the character described comprising a flap pivoted on an airplane and adapted to be moved from an inoperative to an operative position to offer resistance to an air stream, a cylinder mounted on the airplane for movement substantially in alignment with its axis, stops limiting the cylinder movement, a means tending to retain the cylinder at one limit of its travel, a piston in the cylinder having a rod extending therefrom connected to the flap

to move it pivotally, means for admitting hydraulic pressure into one end of the cylinder to move the piston and turn the flap to its operative position, said flap being adapted to be moved towards its inoperative position by excessive air pressure exerted against it and thereby move the cylinder towards its outer limit of travel while the piston is held immovable in said cylinder by hydraulic pressure, and valve means operated by movement of the cylinder for permitting equalization of the hydraulic flow from one end of the cylinder to the other when said cylinder has been moved adjacent its other limit of travel.

6. An arrangement of the character described comprising a pivoted lever, a spring tending to retain it in normal position, a cylinder connected to the lever for movement therewith, a piston in the cylinder, a pivoted flap, a rod extending from the piston and connected to the flap to move the latter, means for admitting hydraulic pressure into one end of the cylinder, said flap being adapted to be turned to its operative position by the piston and towards its inoperative position by excessive air pressure acting against it thereby moving the cylinder and lever, valve means operated by movement of the lever, piping connected to the valve means and cylinder through which a hydraulic flow occurs from one end of the cylinder to the other when said valve means is opened to permit movement of the piston in the cylinder, said spring being adapted to return the lever and cylinder to their normal positions when the air pressure acting upon the flap drops below a predetermined pressure, and means permitting the escape of hydraulic pressure from the other end of the cylinder.

7. The combination set forth in claim 6, including other hydraulic piping and valve means whereby hydraulic pressure may also be exerted in the other end of the cylinder to positively retain the flap in its inoperative position.

8. The combination set forth in claim 6, including other hydraulic piping and electrically operated valve means whereby hydraulic pressure

may also be exerted in the other end of the cylinder to positively retain the flap in its inoperative position.

9. An arrangement of the character described comprising a cylinder mounted for substantially axial movement, a piston therein, means including valves for admitting a pressure medium into either end of the cylinder, mechanical means for selectively operating the valves, a pivoted flap adapted to be moved either to an inoperative position or to an operative position to offer resistance to an air stream, a rod connected to the piston and to the flap to move the latter, said flap being adapted to be moved from its operative towards its inoperative position by excessive air pressure acting thereagainst thereby moving the cylinder when the piston therein is held immovable in said cylinder by the pressure medium, and means tending to return the cylinder to its initial position.

10. An arrangement of the character described comprising a cylinder mounted for substantially axial movement, a piston therein, means including valves for admitting a pressure medium into either end of the cylinder, electrically operated means for selectively operating the valves, a pivoted flap adapted to be moved either to an inoperative position or to an operative position to offer resistance to an air stream, a rod connected to the piston and to the flap to move the latter, said flap being adapted to be moved from its operative towards its inoperative position by excessive air pressure acting thereagainst thereby moving the cylinder when the piston therein is held immovable in said cylinder by the pressure medium, and means tending to return the cylinder to its initial position.

11. An arrangement of the character described comprising the combination set forth in claim 10, including a lever on which said cylinder is mounted, and the electrically operated means being operated through movement of said lever.

ERICH GAST.
